UNITED STATES PATENT OFFICE.

GERTRUDE BARNETT, OF SAN FRANCISCO, CALIFORNIA.

DESIGN FOR A TEAPOT.

Application filed March 5, 1923. Serial No. 5,367. Term of patent 14 years.

To all whom it may concern:

Be it known that I, GERTRUDE BARNETT, a citizen of the United States, residing in the city and county of San Francisco and State of California, have invented a new, original, and ornamental Design for Teapot, of which the following is a specification, reference being had to accompanying drawings, forming part thereof.

Fig. 1 is a side elevation and Fig. 2 a front elevation of a tea pot, showing my new design.

I claim:

The ornamental design for a teapot as shown.

GERTRUDE BARNETT.
